UNITED STATES PATENT OFFICE.

JAMES L. NORRIS, OF WASHINGTON, DISTRICT OF COLUMBIA, ADMINISTRATOR OF WILLIAM PALLISER, DECEASED.

ORDNANCE.

SPECIFICATION forming part of Letters Patent No. 265,984, dated October 10, 1882.

Application filed July 19, 1882. (No model.)

To all whom it may concern:

Be it known that I, JAMES L. NORRIS, a citizen of the United States, residing at Washington, in the District of Columbia, am in possession of an invention for a new and useful Improved Composite Gun, invented by WILLIAM PALLISER, deceased, of which the following is a specification.

This invention relates to an improved construction of heavy guns with an outer casing of cast-steel and an inner lining of coiled wrought-iron and steel, as shown on the accompanying drawing, which shows a longitudinal section of the gun.

The outer casing, C C', is formed of two separate steel castings, screwed together at C'. This casing is turned and then annealed to equalize the strains, and then has the internal screw-thread cut therein for the reception of the coiled wrought-iron lining-tube B. The lining-tube A, which may either be of coiled wrought-iron or of steel, is then first inserted from the breech end, and is secured at the muzzle by the screw-collar P in a similar manner to that described in the patents of William Palliser, after which the tube B is screwed in until its shoulders bear against the shoulders of the casing C, and it is then secured in position by the tubular breech-plug D. The B tube, as also the A tube, when of coiled wrought-iron, are

made to fit easily into the casing, being expanded by the pressure on firing so as to fit the casing closely.

The gun is here shown as a breech-loader, the movable breech-plug F being carried by the hinged collar G and screwed in and out in a well-known manner. When used as a muzzle-loader the end of the B tube would be closed by a cup-shaped plug screwed into it, and behind this a second plug would be screwed into the tubular plug D.

Having thus described the nature of this invention and in what manner the same is to be performed, I claim—

A composite gun consisting of a cast-steel outer casing, C C', formed in two parts screwed together, in combination with a front lining-tube, A, of either coiled wrought-iron or of steel, and a rear lining-tube, B, of coiled wrought-iron screwed into the casing from the breech, substantially as described.

In testimony whereof I have signed my name to this specification before two subscribing witnesses.

JAMES L. NORRIS.

Administrator of the Estate of William Palliser, deceased.
